(57) **CLAIM**

The ornamental design for a temporary power service panel, as shown as described.

DESCRIPTION

FIG. 1 is a perspective view of a temporary power service panel according to a first preferred form of the invention.
FIG. 2 is a left side elevation view of the temporary power service panel of FIG. 1.

FIG. 3 is a right side elevation view of the temporary power service panel of FIG. 1.

FIG. 4 is a front elevation view of the temporary power service panel of FIG. 1.

FIG. 5 is a rear elevation view of the temporary power service panel of FIG. 1.

FIG. 6 is a top plan view of the temporary power service panel of FIG. 1.

FIG. 7 is a bottom view of the temporary power service panel of FIG. 1.

FIG. 8 is a perspective view of a temporary power service panel according to a second preferred form of the invention.

FIG. 9 is a left side elevation view of the temporary power service panel of FIG. 8.

FIG. 10 is a right side elevation view of the temporary power service panel of FIG. 8.

FIG. 11 is a front elevation view of the temporary power service panel of FIG. 8.

FIG. 12 is a rear elevation view of the temporary power service panel of FIG. 8.

FIG. 13 is a top plan view of the temporary power service panel of FIG. 8.

FIG. 14 is a bottom view of the temporary power service panel of FIG. 8.

FIG. 15 is a perspective view of a temporary power service panel according to a third preferred form of the invention.

FIG. 16 is a left side elevation view of the temporary power service panel of FIG. 15.

FIG. 17 is a right side elevation view of the temporary power service panel of FIG. 15.

FIG. 18 is a front elevation view of the temporary power service panel of FIG. 15.

FIG. 19 is a rear elevation view of the temporary power service panel of FIG. 15.

FIG. 20 is a top plan view of the temporary power service panel of FIG. 15; and,

FIG. 21 is a bottom view of the temporary power service panel of FIG. 15.

The broken line showing of the temporary power service panel is for the purpose of illustrating environmental structure and forms no part of the claimed design.
